UNITED STATES PATENT OFFICE.

JOHN T. JOHNSON, OF AKRON, OHIO, ASSIGNOR TO THE AMERICAN RUBBER AND TIRE COMPANY, OF AKRON, OHIO, A CORPORATION OF OHIO.

DESIGN FOR A BATHING SLIPPER.

Application filed May 23, 1923. Serial No. 6,258. Term of patent 3½ years.

To all whom it may concern:

Be it known that I, JOHN T. JOHNSON, a citizen of the United States, residing at Akron, in the county of Summit and State of Ohio, have invented a new, original, and ornamental Design for a Bathing Slipper, of which the following is a specification, reference being had to the accompanying drawings, forming a part thereof.

In the drawings:

I claim:

The ornamental design for a bathing slipper, as shown.

JOHN T. JOHNSON.
